DESIGN FOR A TOP SHELL FOR A WRIST WATCH BRACELET

Eric G. O. Anderson, Cranston, R. I., assignor to
Everfine Jewelry Manufacturing Company,
Providence, R. I., a corporation of Rhode Island

Application July 3, 1947, Serial No. 140,085

Term of patent 3½ years

(Cl. D45—4)

To all whom it may concern:

Be it known that I, Eric G. O. Anderson, a citizen of the United States of America, residing at Cranston, in the county of Providence and State of Rhode Island, have invented a new, original, and ornamental Design for a Top Shell for a Wrist Watch Bracelet, of which the following is a specification, reference being had to the accompanying drawing, forming part thereof.

Figure 1 is an enlarged perspective view showing a top shell for a wrist watch bracelet; and

Figure 2 is an enlarged view of the shell in side elevation.

I claim:

The ornamental design for a top shell for a wrist watch bracelet, as shown and described.

ERIC G. O. ANDERSON.
